United States Patent Office

Des. 180,221
Patented May 7, 1957

180,221

WALL PANEL

Philip Carver, Bayside, N. Y.

Application June 16, 1955, Serial No. 36,535

Term of patent 7 years

(Cl. D13—1)

Fig. 1

Fig. 2

Fig. 3

Figure 1 is a front elevational view of a wall panel showing my new design;

Figure 2 is a fragmentary end elevational view thereof to a slightly larger scale; and

Figure 3 is a fragmentary side elevational view, to a slightly larger scale taken from the left of Figure 1 between the bottom and central groove.

I claim:

The ornamental design for a wall panel, as shown.
